SIFTER FOR FEED-MILLS.

1,362,725.

Specification of Letters Patent.

Patented Dec. 21, 1920.

Application filed August 1, 1918. Serial No. 247,731.

To all whom it may concern:

Be it known that I, GEORGE E. W. MARSDEN, a citizen of the United States, residing at Beloit, in the county of Rock and State 5 of Wisconsin, have invented certain new and useful Improvements in Sifters for Feed-Mills, of which the following is a specification.

This invention relates to a feed mill of 10 the type which is employed for grinding cereals or other food into meal or flour, and the invention refers more particularly to a screen and means for reciprocating the same to sift the ground meal and separate 15 the finer from the coarser particles thereof.

The invention aims to provide a sifting means which is extremely simple and durable and which is operated from the main grinder shaft.

20 In the accompanying drawings Figure 1 is a side elevational view, with parts broken away, illustrating a feed mill equipped with sifting means embodying my invention. Fig. 2 is a horizontal sectional view taken in 25 the plane of line 2—2 of Fig. 1. Fig. 3 is a vertical sectional view on line 3—3 of Fig. 1.

The feed mill which I have shown by way of example in the drawings comprises a body 5, which may be an integral casting, and 30 which in the present instance has strengthening ribs or webs 6 projecting in opposite directions from the ends thereof.

The grinding chamber is indicated at 7, and 8 indicates a hopper, the upper portion 35 of which is broken away, which hopper receives the material to be ground and feeds it to the grinding chamber. The grinding means is not herein shown, as the present invention is not concerned therewith, but 40 said means is operated by a shaft 9 which is rotatably mounted in bearings in the body 5 and is arranged to be driven in any desired way.

Beneath the outlet from the grinding 45 chamber is a sifter 10 comprising side walls and a perforated or reticulated bottom wall. The sifter is supported in an inclined position and the side at the lower end of the 50 sifter is open so that in the reciprocation of the sifter, the finer particles will fall through and the coarser particles will roll down the bottom wall and off the end thereof. A suitable number of ribs 11 may be provided along the bottom of the sifter

to retard the meal in its tendency to roll 55 down the incline.

In the present instance the sifter is mounted upon the ends of two rods 12 which are supported and guided to reciprocate in apertures or notches 13 in the webs 6 at one 60 end of the body. The opposite ends of these rods are attached to the lower end of a bifurcated lever 14, the branches of which straddle the mid-portion of the body 5. This lever is pivoted at 15 on an upstanding lug 65 on the body, and the upper end of the lever extends laterally, or in other words the lever is of inverted L-shape. A cam or eccentric 16 is fixed upon the shaft 9 in position to bear against the upper end of the 70 lever, so that in the rotation of the cam the lever will be oscillated. A pair of springs 17 located at opposite sides of the body have their ends attached respectively to the lever 14 and to an anchor 18, which is in the form 75 of a U-shaped wire embracing the body, the arms of the anchor being bent into engagement with the flanges 6 on the body to secure the anchor in place.

The springs 17 hold the lever 14 in contact 80 with the cam 16 so that the sifter 10 will be reciprocated when the mill is in operation.

I claim as my invention:

1. A feed mill having, in combination, a body, a grinding shaft, a cam fixed on said 85 shaft, an upright lever pivoted between its ends on the body and having its upper end bearing against said cam, the lower portion of the lever being bifurcated to straddle the body, a pair of springs attached to the lower 90 arms of the lever to maintain the lever in contact with the cam, a reciprocatory sifter, and a pair of rods each attached at one end to the sifter and at its other end to one of the arms of said bifurcated lever. 95

2. A feed mill having, in combination, a supporting body, a drive shaft, means on said body horizontally reciprocable parallel to said drive shaft and carrying a sifter, a single cam-actuated element adapted to move 100 said reciprocable means in one direction, resilient means for moving said reciprocable means in the opposite direction, and a radially acting cam mounted directly on the drive shaft of the mill and engaging said 105 cam-actuated element.

3. A feed mill having, in combination, a supporting body, a central hopper, and a

front grinding chamber carried by said body, means reciprocable horizontally parallel to the drive shaft of the mill, comprising a sifter under said grinding chamber and a member supporting said sifter and extending under said hopper, a single cam-actuated element connected to said support-

ing member at the rear of said hopper, and a cam on the drive shaft of said mill engaging said cam actuated element. 10

In testimony whereof I have hereunto set my hand.

GEORGE E. W. MARSDEN.
